UNITED STATES PATENT OFFICE.

ADDELBERT DUDGEON, OF LATROBE, PENNSYLVANIA, ASSIGNOR OF ONE-FOURTH TO
J. H. WILLOUGHBY AND ONE-EIGHTH TO A. E. EWING, BOTH OF LATROBE, PENN.
SYLVANIA.

COMPRESSOR.

1,122,085.

Specification of Letters Patent. Patented Dec. 22, 1914.

Application filed October 8, 1913. Serial No. 794,104.

To all whom it may concern:

Be it known that I, ADDELBERT DUDGEON, a citizen of the United States, residing at Latrobe, in the county of Westmoreland 5 and State of Pennsylvania, have invented new and useful Improvements in Compressors, of which the following is a specification.

The invention relates to an improvement 10 in compressors and particularly to a means for operating a series of compressors in an even and uniform manner.

The main object of the present invention 15 is the provision of a compressor operating device including a rotating element having cam and pin connection with the piston stem of a plurality of compressors, the construction providing for the adjustment of the connection to vary the stroke of the piston 20 or pistons at will.

The invention in its preferred form of 25 details will be described in the following specification, reference being had particularly to the accompanying drawings, in which—

Figure 1 is a longitudinal sectional view showing two compressors coupled to the improved operating means. Fig. 2 is an end elevation of the same. Fig. 3 is a trans- 30 verse section of the same.

In the accompanying drawings, the improved operating means designated generally by 1 is shown as connected to two double compressors designated generally by 2 which as shown are duplicates of each other. The compressors comprise cylinders 3 having heads 4 and offsets 5, whereby they may be bolted as at 6 to an appropriate base 7. Within the cylinder 3 are mounted 40 pistons 8 connected for simultaneous movement through a piston rod 9.

Mounted centrally between the cylinders 3 is a drive shaft 10, preferably supported in bearings 11 rising from the base plate 7. 45 Centrally of the valve of the cylinders the shaft is enlarged at 12 on which through the medium of the key 13 is secured a sleeve 14, formed with a cam channel 15 in its outer surface, the channel extending circumferentially of the sleeve, so as to present its maximum operating portion approximately at the respective ends of the sleeve. The cam sleeve 14 is of such diameter as to project within the plane of the cylinders 3,

the latter being cut away at 16 to receive 55 the sleeve.

Slidably mounted upon each piston rod 9 is a connector 17, comprising a cruciform element centrally formed with an opening 18 to slidably engage the piston rod. 60 The connector is provided with a threaded opening 19 extending at right angles to the opening 18 for the reception of the threaded stud 20, the outer terminal of which projects through a slot 21 in the cylinder 3 and is 65 provided with a head 22 for wrench application. By means of the stud 20 it is obvious that the connector may be locked in any desired position upon the piston rod 9 within the limits of the slot 21. From the 70 connector at a point diametrically opposite the stud 20 there is extended a shaft 23, the free terminal of which is designed to fit in the cam groove 15 of the sleeve 14, the terminal of the shaft being if desired in the 75 form of a freely rotatable roller to avoid friction. The connector is further guided in movement by a stud 24 extending therefrom at right angles to the shaft 23 to a screw stud 20, which stud is guided in the 80 slot 25 formed in the cylinder 3.

From the above description, it will be apparent that in the rotation of the shaft 10 the cam sleeve is correspondingly rotated with the effect to reciprocate the pistons 85 within the cylinders for the desired compression of their effect. It is obvious that any number of cylinders may be operatively connected to the cam sleeve, the cylinders being arranged in annular series. 90

The improved operating device insures a smooth noiseless operation, eliminates crank connection, and requires comparatively little power to drive it.

What is claimed is:—

In combination, a pair of cylinders having an operating mechanism therein including piston rods, a frame connecting the cylinders together, a drive shaft positioned intermediate said cylinders, said shaft having an enlargement formed thereon intermediate the ends of the cylinders, bearings for said shaft and contacting with the ends of said enlargement for preventing end thrust thereof, a sleeve detachably mounted 100 on said enlargement and formed with a cam groove, connectors of cross-form adjustably mounted on said piston rods, said

- connectors having a portion of their outer surface contact with the inner walls of said cylinders for supporting the intermediate portion of said piston rods, stub shafts projecting from said connectors and engaging a cam groove, a second set of stub shafts projecting from said connectors and slidably in the walls of said cylinders, and threaded studs passing through slots in the walls of the cylinders for adjustably connecting said connectors to said piston rods, said second set of stub shafts and threaded studs adapted to prevent displacement of said connectors with relation to said sleeve. In testimony whereof I affix my signature 15 in presence of two witnesses.

ADDELBERT DUDGEON.
